ELECTRICAL CONDUCTOR CABLE

John L. Alden, La Grange, Ill., assignor to Western Electric Company, Incorporated, New York, N. Y., a corporation of New York

Application May 12, 1933, Serial No. 670,698

2 Claims. (Cl. 173—264)

This invention relates to electrical conductor cables and more particularly to multiconductor cables intended for uses in which the cables are subjected to repeated flexure.

5 A principal object of the invention is to provide a cable of the character described which is of high conductivity and at the same time of great endurance under repeated flexure.

With this and other objects in view, one embodiment of the invention contemplates conductor strands composed of a plurality of ribbons of conductive material wound upon a central non-conductive supporting strand, a binding and protective layer of textile strands binding together the combined strands of the conductors, a sheath of electrically insulating material upon the textile binding of the conductors, a sheath of heat insulating material there over, and an outer layer of binding and protective textile strands over all.

Other objects and characteristic features of the invention will appear from the following detailed description of one embodiment of the invention taken in connection with the accompanying drawing in which

Fig. 1 represents a view of a piece of conductor cable constructed in accordance with the invention and progressively frayed out at one end to show the various elements combined in the structure, and

Fig. 2 is an enlarged view of a piece of one of the conductor strands.

In the embodiment herein disclosed the cable comprises two conductor strands 10 and various protective and uniting sheaths. Each of the two conductors 10 consists of a plurality of intertwined strands 11 each having a central non-conducting supporting core 12 preferably of textile thread spun from cotton or the like which has been previously thoroughly freed from deleterious or metal corrosive substances. So far as the conductor strands 11 are concerned, the cores 12 are chiefly designed to provide tensile strength and to relieve the conducting elements themselves of tensile stress and at the same time to afford minimum resistance to flexure. Upon each of the cores 12 is wound the actual electrically conducting element comprising two or more tape-like flat ribbons 13 of metal, preferably wound one on top of the other in an open non-self contacting helix upon the core 12 as shown, although in some instances these ribbons may be laid upon the core 12 side by side or only partially overlapping. The ribbons 13 are preferably of copper of utmost practicable purity

in order to afford the highest degree of both mechanical flexibility and flexure endurance and of electrical conductivity.

A plurality of such conductor strands 11 each comprising as described a central non-conducting core and two or more conducting ribbons wound thereon in an open helix, is then combined to form the core of a principal conductor generally indicated by the numeral 14, the number of strands 11 thus composing a principal conductor depending upon the relation between the current carrying capacity of an individual strand 11 and the purpose for which the completed cable is intended. In one instance where the cable is intended for household heating appliances of comparatively heavy power consumption such as flat irons, hot plates, etc., each principal conductor comprises nineteen conductor strands. Although conductor strands in the form of flat ribbons are preferred, some of the advantages of the invention may be obtained by using small round conductive wires arranged in the manner herein described.

Each assembly of conductor strands 11 combined into a principal conductor is provided with a binding cover of textile threads 15 preferably wound on over the conductor, although in some instances they may be braided together over the group of conductor strands instead of being wound thereon. A layer of electrically insulating material 16 is deposited on the binding threads 15 in a seamless sheath as shown. This insulating material 16 is preferably a soft, tough and pliable compound of rubber or the like having a high degree of flexibility and electrical insulating quality as well as a composition innocuous to the chemical composition of the underlying metal ribbons. Such compounds may be made with a rubber material as base which contains substantially no free sulphur. Even so the interposed textile layer 15 is preferably made sufficiently dense to prevent any direct contact of the electrically insulating material 16 with the metal ribbons.

Over the electrically insulating sheath 16 is applied a layer of thermally insulating material 17. This may be a layer of strands spun from fibrous asbestos or analogous material wound or otherwise applied over the sheath 16. Preferably the thermally insulating material is applied in such a way as to be fluffy and porous in texture so that the entrapped air will aid in rendering the layer heat proof.

As herein disclosed two principal conductors 14 constructed as described are intertwined

- and finally provided with an outer binding and protective covering of textile strands 18, preferably braided on, although in some instances it may be satisfactory to wind or spin the strands 18 in place. Evidently more than two principal conductors may be thus combined into a multi-conductor cable if desired. Also in some cases it may be preferable to combine the principal conductors without twisting.
- 10 The various details of characterizing construction thus combined provide a cable of vastly improved flexibility and endurance. In one instance a cable constructed as described showed an average endurance of 44200 and a maximum of 50861 cycles of flexure before failure when tested by the Underwriters' Laboratories. The standard requirement for such cables is 3000 cycles for cables intended for household use with electric flatirons and one cable of customary construction now on the market has endured 12000 cycles.
- 15 The embodiment of the invention herein disclosed is illustrative merely and may be modified and departed from in many ways without departing from the spirit and scope of the invention as pointed out in and limited only by the appended claims.
- 20
- 25

What is claimed is:

1. In a conductor cable, a plurality of inter-

twisted principal conductors each comprising a plurality of conductor strands intertwisted without a core strand and each composed of a plurality of flat ribbons of conductive material wound in an open helix upon a central non-conductive core, a sheath of non-conductive binding strands upon each plurality of conductor strands, a sheath of electrically insulating material over each sheath of binding strands, a sheath of thermally insulating material over each sheath of electrically insulating material, and an outer binding sheath of non conductive strands braided over the whole.

2. In a conductor cable, a plurality of inter-twisted principal conductors each comprising a plurality of conductor strands intertwisted without a core strand and each composed of two flat ribbons of copper wound in an open helix upon a central textile core, a sheath of textile binding strands wound upon each plurality of conductor strands, a sheath of rubber base electrical insulation over each sheath of binding strands, a sheath of asbestos base thermal insulation over each rubber base sheath, and an outer binding sheath of textile fibres 20 braided over the whole.

JOHN L. ALDEN.
